UNITED STATES PATENT OFFICE

DANIEL McLEOD, JR., OF DALLAS, TEXAS

CLIP

Application filed January 6, 1930. Serial No. 418,956.

This invention relates to new and useful improvements in clips.

One object of the invention is to provide an improved clip of superior construction for use in binding sheets of paper and other material.

A further object of the invention is to provide a clip of simple construction and including clip members connected by an elongated bar whereby the clip lends itself to ready and convenient use for binding together the edges of two or more sheets and serves to hold the edges of said sheets in alinement.

An important object of the invention is to provide an elongated clip which may either be used to bind a plurality of sheets or which may be inserted in a folder to provide a resilient binder for clipping a plurality of sheets therein.

20 A further object of the invention is to provide an elongated clip utilizing a minimum of material and thus making for simplicity and economy in construction.

Another object of the invention is to provide a clip in which the connecting bar is positioned close to the marginal edge of the uppermost sheet and also in which the ends of the clip members extend on the opposite side of the bar from the loops, thus making a clip 30 more easy to apply and detach, and avoiding puncturing of the sheets by sharp ends of the clip members.

A construction designed to carry out the invention will be hereinafter described together with other features of the invention.

The invention will be more readily understood from a reading of the following specification and by reference to the accompanying drawings in which an example of the invention is shown, and wherein:

Figure 1 is a view of a clip constructed in accordance with the invention,

Figure 2 is an enlarged cross-sectional view taken on the line 2-2 of Figure 1,

45 Figure 3 is a view showing the clip binding several sheets of paper,

Figure 4 is a similar view showing one of the sheets folded back over the clip,

50 Figure 5 is a view of an open folder showing the clip applied thereto as a binder, and

Figure 6 is an enlarged cross-sectional view taken on the line 6-6 of Figure 5.

In the drawings the numeral 10 designates the connecting bar of the clip, which has at each end clip members 11. The bar may be 55 of any length within reason and I have successfully used clips ten (10) inches long, however, clips four (4) inches long have proved equally as satisfactory, and the invention is not to be limited to the length of 60 the clip. The clip may be made of resilient wire suitably finished and such as is now in common use in this art.

At each end of the bar 10 the wire is bent at substantially right-angles to said bar and 65 then bent upon itself to form comparatively narrow loops constituting the end members. The bends may be comparatively sharp, but need not be exactly at right-angles. The wire is bent inwardly and the legs 12 of the 70 loops extend across the bar 10 at substantially right-angles thereto. The ends of the legs 12 are coiled upon themselves to form eyes 13 and these eyes are turned outwardly toward the end of the bar. It will be seen 75 that this structure eliminates all sharp ends and by bending the legs 12 so as to contact with the bar 10, clamps are provided.

In Figure 3 the clip is shown applied as a binder to a plurality of sheets A. If these 80 sheets are letter size, the clip may be made long enough to extend along the major portion of one edge of each sheet. It is pointed out that the clip is very easy to apply to the sheets and it is simply necessary to grasp one 85 of the loop members 11 between the thumb and forefinger and slip one member over the edges of the sheets and then grasp the other loops member and slip it over the edges. The single bar 10 will extend across the top 90 sheet and will lie close to the edge thereof. The eyes 13 will lie inwardly from the bar, thus securely clamping the clip in place. The sheets may be readily folded back, as is shown in Figure 4. It is obvious that the 95 clip may be quickly pulled from the sheets without danger of puncturing or injuring the same.

One of the great advantages of this clip is that the eyes 13 and legs 12 may be passed 100

through apertures B in a filing folder C and the clip thus utilized as a binder. A plurality of sheets D may have one edge engaged under the bar 10 and the exposed portions of 5 the loop members 11. It is obvious that the same clip may be removed from the sheets A, inserted in the folder C and the said sheets secured under the bar 10 in said folder, or the clip may be removed, the sheets taken out 10 of the folder and fastened by the clip, as shown in Figure 3. The fact that the loop members have only one element crossing the bar 10 and the whole clip being of a flat construction makes for its efficiency and 15 utility.

Various changes in the size and shape of the different parts, as well as modifications and alterations, may be made within the scope of the appended claims.

20 What I claim, is:

1. A clip comprising an elongated bar having a loop at each end formed by three bends, the first bend being at right angles to the bar, the second bend being inwardly and 25 the third bend being downwardly toward the bar, the loops being substantially in the plane of the bar, the extremity of each loop normally engaging the bar and extending on the opposite side thereof from the loop, 30 and eyes on the extreme ends of the loop extremities bent therefrom.

2. A clip comprising a straight elongated bar having its ends bent at an angle thereto and then rebent inwardly and parallel to 35 the bent portion to form loops, the free end of said rebent portion being normally in contact with the bar and terminating at the side thereof opposite the loop.

3. The clip defined by claim 2, in which 30 said terminations are formed as outturned eyes.

In testimony whereof I affix my signature.

DANIEL McLEOD, JR.
